(57) **CLAIM**

The ornamental design for a display screen or a portion thereof with a graphical user interface, as shown and described.

DESCRIPTION

The sole FIGURE is a front elevational view of the display screen or portion thereof with a graphical user interface in accordance with the new design. The broken lines showing the display screen or portion thereof and the broken lines showing the remainder of the graphical user interface are for environmental purposes only and form no part of the claimed subject matter.
